ADJUSTABLE AWNING FOR USE ON BOATS,
BEACHES, AND ELSEWHERE

Charles George Heisig, St. Albans, N. Y.

Application February 3, 1949, Serial No. 74,307

1 Claim. (Cl. 135—6)

1

This invention relates to an adjustable awning for use on small boats, on beaches, on private homes and elsewhere.

The awning constituting the present invention is universal in its construction and use. It is adaptable for attachment to the side of a house, as for example, above the porch. It is also mountable upon a boat and more particularly a small boat such as a rowboat, sailing boat, motor-boat or the like. It is equally adaptable for use on the beach or a lawn, or in picnic grounds and similar locations.

One of the principal features of the awning herein described and claimed is a clamping bracket which is adaptable for mounting upon the sides or gunwales of a rowboat of the type used on inland waters for fishing purposes. Similarly the clamping bracket of the present invention is adaptable for mounting on a stake driven into the ground whether in a lawn or on the beach. When the awning is to be used on the side of a building, such as a private home, suitable supports may be provided on which the clamping bracket is to be mounted.

Apart from its adaptability to boats, beaches, private homes and the like, the awning herein claimed is adapted for adjusting to any desirable position. For example, if it should be so mounted on a beach as to provide protection against the morning sun, very little adjustment is needed to change its position to provide protection against the noonday and afternoon sun. It need not be removed from its mounting in order to provide such change in position.

Another important feature of the present invention is the fact that the awning or canopy proper is of elongated rectangular shape. This adapts it for use on a rowboat, as the drawing clearly shows, since it covers those parts of the boat which accommodate the fisherman. Heretofore umbrella-shaped awnings have been employed on rowboats as well as on beaches and lawns, but it is clear from the shape of these awnings that inadequate protection against the sun must necessarily be provided. An umbrella-shaped awning may suffice where one person is concerned, but where two or more persons seek the protection of its shade, it is quite inadequate.

Still another important feature of the present invention is the fact that its supporting arms are offset for mounting upon a support which is off to the side of the awning proper. In umbrella-shaped awnings, the supporting shaft extends centrally of the awning or canopy proper. In the present invention, the supporting arms are bent

5 to extend laterally as well as downwardly, with respect to the center of the awning. Thus it is that these supporting arms may be clamped to the sides of a rowboat but the awning proper will remain supported centrally of the rowboat. The adjusting feature of the present invention, above referred to, is located centrally of the awning. By reason of this adjusting feature, the awning may be tilted to either side of the rowboat irrespective of the side to which the supporting arms are clamped. It will be clear, therefore, that although the supporting arms are clamped to the starboard side of the boat, the awning may be tilted to port side and conversely the supporting arms may be clamped to the port side and the awning tilted to the starboard side. In either case, the awning may, of course, be held in a central position relative to the two sides of the boat or it may be tilted to that side on which the supporting arms are mounted.

10 A further feature of the invention is the adaptability of the bracket clamps for mounting on supports which are in alignment or disalignment with each other. The curved side of a rowboat is illustrative. Despite this curvature, the bracket clamps are readily attachable to either or both sides of the rowboat. Both clamps, and hence the supporting arms, may be attached to one side of the rowboat at any one time, or to the other side of the rowboat at any one time, or one of the clamps may be mounted on one side and the other on the opposite side. When the clamps are fastened to stakes driven into the ground, it is immaterial that the stakes may not be in perfect alignment with each other. The construction of the bracket clamps is such as to compensate for disalignment whether in the sides of a rowboat or in stakes driven into the ground.

15 Still another object and feature of the present invention is the feature which renders the awning frame adjustable to changes in dimensions of the awning. It is well known that an awning of given dimensions in a dry state possesses different dimensions in a wet state. The frame which supports the awning in the present invention is readily adjustable to compensate for such dimensional changes in the awning.

20 The awning supporting frame is adjustable in still another sense. It is adjustable to accommodate larger or smaller awnings. The awning frame is telescopically adjustable so that longer or shorter awnings may be accommodated without the slightest bit of difficulty.

25 Although the awning has hereinabove been described solely in terms of its being a shield

against the rays of the sun, it is equally useful as a windbreaker, since it may be tilted a full 180°. The awning is generally maintained in a horizontal or nearly horizontal position. It may, however, be tilted to a vertical or nearly vertical position for the purpose of protecting the occupants of the rowboat or the bathers on the beach against the wind. Similarly the awning may be used to protect them against the rain, since the material of which it is made should preferably be highly resistant to water.

Another important feature of the awning herein described and claimed is that it is readily portable, so that it may very conveniently be carried or transported from place to place. This feature stems from the fact that the frame of the awning is collapsible or demountable, so that it may be reduced to the proportions of a relatively small, handy package. It may be assembled wherever it is to be used without the need of special tools or equipment.

A further important feature of the invention is the free, uncluttered space which it provides under its canopy. Its supporting arms are offset relative to the canopy leaving a wholly unoccupied and fully usable space underneath said canopy. This feature is especially valuable in small boats where a central support for the canopy would obstruct free movement of the occupants centrally of the boat, which is necessary to avoid rocking the boat.

Preferred forms of this invention are shown by way of illustration in the accompanying drawing in which:

Fig. 1 is a perspective view of an awning made in accordance with the present invention, showing said awning mounted on a rowboat;

Fig. 2 is an enlarged, fragmentary end view of said awning, partly in vertical section;

Fig. 3 is a view of one of the toothed adjusting members of said awning;

Fig. 4 is a similar view of the complementary part of said toothed member, showing the sprung-tongue, which engages the teeth of said toothed member;

Fig. 5 is an enlarged fragmentary section on the line 5—5 of Fig. 2;

Fig. 6 is a view of one of the clamping brackets by which the awning is mounted on the side of the rowboat;

Fig. 7 is an enlarged fragmentary view in section on the line 7—7 of Fig. 2;

Fig. 8 is an enlarged fragmentary sectional view through the nut portion of the longitudinally adjustable frame of said awning;

Fig. 9 is an end view thereof;

Fig. 10 is a transverse section on the line 10—10 of Fig. 8;

Fig. 11 is a view of the swivel mechanism of Fig. 2, looking in the direction of the arrows 11—11 of Fig. 2; and

Fig. 12 is a fragmentary view, similar to the lower portion of Fig. 2, showing a second type of supporting bracket by which the awning frame may be mounted on the side of the boat.

The awning of the present invention comprises a cover or canopy 20, a frame 21, supporting said canopy, and brackets 22, which are adapted to clamp said frame to any suitable support, such as the sides of a row boat 23 or the tops of stakes driven into the ground.

The canopy is preferably of elongated rectangular shape as Fig. 1 of the drawing clearly shows. It has a top portion 25, and four downwardly extending side portions or curtains 26.

The lower portions of said curtains may be scalloped as shown at 27 in Fig. 2. The material of which the canopy should preferably be made is the type of material that would best resist the effects of exposure to sun, salt water and other elements commonly encountered in the outdoors. It should also be sufficiently strong to withstand the strains and stresses imposed by strong winds. Awning material rendered moisture and mildew resistant would be suitable. A rubberized material or plastic coated material might also be suitable for the purposes of this invention. Duck would also be a suitable material, if its weight is not objectionable.

The frame which supports the canopy is H-shaped, wherein the cross piece of the H extends longitudinally of the canopy and the two side members of the H parallel the two end portions of the canopy. These two side members of the H-shaped frame are designated in the drawing by means of the reference character 30. They are shown to be made of tubular material extending from one side of the canopy to the other. They occupy the angular space formed between the top of the canopy and its two end curtains. See Figs. 5 and 7. A tape 31 is attached by means of stitches 32 and 33 to the top and each end of the canopy, thereby forming a pocket to accommodate tube 30 of the H-shaped frame. This tape prevents accidental displacement of the tube relative to the canopy.

Each tube 30 has a pair of plates 35 affixed thereto, centrally thereof, by means of rivets 36. These plates extend downwardly from the tubes, one on each side of each tube, in parallel planes. They serve a purpose which will shortly be described. Affixed to each tube 30 and to the inner of the two plates 35 is a pin 38. This pin extends centrally of the tube as well as centrally and longitudinally of the canopy.

The cross member of the H-shaped frame supporting the canopy is telescopically adjustable and it comprises an inner tube 40, which is in telescopic engagement with an outer tube 41. Considering the two tubes 40 and 41 as constituting a single telescopically adjustable frame member, it will be seen that one end of said member is engageable with one of the pins 38 and the other end of said member is engageable with the other of said pins 38. See Fig. 7. In order to attach said telescopically adjustable member to the two end members of the H-shaped frame, all that need be done, therefore, is to slip one end of said telescopically adjustable member on to one of said pins 38 and the other end on to the other of said pins 38. Screw means are provided in the telescopically adjustable member to fix its two tubular portions relative to each other. A preferred form of such screw means is shown in Figs. 7 to 10 inclusive.

The screw means above mentioned comprises a nut 45 and a cooperating screw 46. The nut may be fastened to the inner end of the smaller tube 40 and the screw may be fastened to the inside of the larger tube 41. Reference to Fig. 10 will disclose the fact that nut 45 is provided with a plurality of radially extending lugs or ears 47 and it will be seen in Fig. 9 that corresponding cutouts 48 are formed in the end portion of tubular member 40. These lugs are engageable with the cutouts to prevent relative angular movement between the nut and the tube. The end of the tube is peened over or upset at 49 to prevent the nut from falling out of said tube.

The head 50 of bolt 46 is affixed by means of

pin 51, or by any other suitable means, to the inside of tube 41 to prevent relative movement between said bolt and said tube. A block 52, having a hole formed therein, is mounted on the shank of the bolt to prevent the bolt from wobbling in tube 41 and to maintain it in a central position relative to said tube.

When it is desired to join the telescopically adjustable centrally extending frame member to the two end frame members, the two tubes 40 and 41, which comprise said telescopically adjustable frame member, are joined to each other in the manner shown in Fig. 7 and screw 46 and nut 45 are thereby brought into engagement with each other. The tubes 40 and 41 are rotated relative to each other until they are drawn together sufficiently, to enable them to enter the space between the two pins 38. The two tubes 40 and 41 are then lined up with said pins and they are again turned relative to each other in the opposite direction. This causes elongation of said telescopically adjustable member and its two ends are thereby brought into engagement, respectively, with the two pins 38. Further, the turning of the two tubes 40 and 41 relative to each other causes them to press against the inner plates 35 to place the canopy under tension. The telescopically adjustable frame member may be removed from the canopy by simply screwing it out of engagement with pins 38.

Affixed to each pair of plates 35, by means of rivets 50a, is a downwardly extending tubular member 51a. This tubular member is in telescopic engagement with a larger or outer tubular member 52a, as is clearly shown in Figs. 2 and 7. The inner tube is provided with a plurality of holes 53 and a pin 54, extending through a corresponding hole in tube 52a engages one of said holes 53 to prevent relative movement between said tubes 51a and 52a. More than one hole 53 is provided in tube 51a, so that said tube may be adjustably positioned relative to the other tube 52a. Each pair of tubes 51a and 52a may be considered to comprise a single telescopically adjustable side frame member and there are two such members, one at each end of the canopy.

The lower end of each of the telescopically adjustable members last above described is pivotally connected to the upper end of one of the supporting arms 21, as above mentioned. The lower end of each supporting arm is connected to one of the clamping brackets 22, also first above mentioned. See Fig. 2. It will there be seen that each supporting arm 21 is bowed, so that its lower end extends in a substantially vertical line and its upper end approaches the horizontal. Affixed to the upper end of each bowed supporting arm 21 by means of rivets 68, is a pair of notched members 61. These notched members are substantially disc-shaped, having a centrally extending hole 62 and spaced notches 63 formed peripherally thereof. Affixed to the lower end of each tube 52 is a pair of disc-shaped plates 65, spaced from each other, and provided with centrally extending holes 66. Rivets 67 affix said plates to said tube. Plates 65 are so spaced relative to each other as to enable them to accommodate notched plates 61 between them. A pair of notches 68 are formed in plates 65 and it will be understood that said notches are situated for registration with the notches 63 of plates 61. A bolt or rivet 69, extending through holes 66 and 62 fasten said plates 65 to said plates 61.

It is by means of this construction that the adjustable side frame members are pivotally con-

nected to said supporting arms 21. A bracket 70 is fastened to each of said adjustable side frame members by means of the same rivets 67, which affix plates 65 to said side frame member.

5 Mounted on said bracket 70 is a leaf spring 71 to which a tongue 72 is affixed. This tongue is so positioned, under the tension of spring 71, as to bring it into engagement with notches 68 of plates 65 and with notches 63 of plates 61. Actually tongue 72 is in engagement with any one pair of registering notches 63 at any one time, and the position of the adjustable side frame member relative to its supporting arm 21 is determined by which pair of notches tongue 72 happens to engage. A finger piece 73 is affixed to tongue 72, so that the tongue may be removed from engagement with one pair of notches 63 to bring it into engagement with any other pair of such notches 63.

20 To change the relative positions of the side frame members and the supporting arms 21, tongue 72 is removed from engagement with one pair of notches 63, the side frame members are then moved relatively to the supporting arms, 25 and the tongue 72 is then released for engagement with another pair of notches 63. Spring 71 will hold the tongue in engagement with said notches until the tongue is manually moved out of engagement therewith, by means of finger piece 73.

30 The clamping bracket 22 comprises a substantially U-shaped member 80, which is adapted to slip over the side of a rowboat, as Fig. 2 clearly shows, or onto a stake driven into the ground. 35 Two clamping screws 81 are connected to said bracket and it will be noted that each screw has a contact member or button 82 which is swivelly mounted thereon. A pair of U bolts 84 fasten the lower end of supporting arm 21 to one side 40 of the U-shaped bracket member 80. If necessary, a wedge-shaped block 85 may be provided between the button 82 of the clamp screw, and the gunwale 86 of the boat. Said wedge-shaped block may, of course, be placed on the opposite or outer side of the gunwale, if desired. Bolts 86 45 in said supporting arm 21, above and below U bolts 84, prevent longitudinal displacement of said supporting arm relative to said bracket 80.

50 It will be appreciated that the connection between supporting arm 21 and bracket 22 is in the nature of a pivotal connection, so that said supporting arm may be turned relatively to the bracket or the bracket relatively to the supporting arm. It is this feature which enables the structure to be mounted on the curved gunwale 55 of a rowboat or upon a pair of stakes, which are not in accurate alignment with each other.

55 Referring now to Fig. 12 it will be seen that a modified form of clamping bracket is therein illustrated. This bracket includes a U-shaped member 90, which is similar to U-shaped member 80 above described. Clamping screws 91 are provided in said U-shaped member similar in all essential respects to clamping screws 81 aforementioned. Instead, however, of making use of U bolts 84, the present form of clamping bracket 60 includes a tubular socket member 92, which is fastened to the U-shaped member 90 and is rigidly reinforced thereon by means of rib 93. The lower end of supporting arm 21 extends into and through tubular member 92. A collar 94, which is pinned to arm 21, prevents said arm from slipping downwardly through tubular member 92 beyond a predetermined point. A cotter pin 95 65 on the downwardly and outwardly projecting end 70

of said supporting arm prevents the arm from being pulled upwardly through the tubular member 92, as when a strong gust of wind strikes the canopy at a favorable angle. Pin 95 is, of course, removable for the purpose of removing the supporting arm 21 from tubular member 92, when it is desired to do so. It will be observed from the foregoing that supporting arm 21 is free to turn in its tubular supporting member 92.

The frame members above described, which support the canopy, are made, preferably, of strong aluminum alloy, principally aluminum tubing, such as is frequently used for structural purposes in aircraft construction. Such material is light and strong and it adequately serves the purposes of the present invention. It is resistant to the corrosive action of sea water and the moisture laden air common to beaches and similar locations. The clamping bracket may, however, be made of steel, if aluminum alloy is found to be too weak for clamping purposes. If a ferrous material is used in the clamps, it should, of course, be adequately protected by galvanizing it or in any other conventional manner providing it with a protective coat.

The foregoing is illustrative of the broad principles of the invention and it will be understood that changes and modifications may be incorporated therein within the broad scope and spirit of the invention.

I claim:

In a canopy frame, a pair of bowed lower supporting arms whose upper ends are offset from the lower ends, a pair of upper supporting arms pivotally connected at their lower ends to the offset upper ends of the lower supporting arms,

selectively adjustable locking members on the pivotal connections between the upper and lower supporting arms for locking the upper supporting arms in selected angular positions relative to the lower supporting arms, a horizontal frame member secured at its ends to the upper ends of the upper supporting arms, and a pair of transverse frame members which are secured intermediate their ends to the ends of the horizontal frame member, said horizontal frame member comprising a tubular member, a rod being provided which is accommodated by said tubular member in telescopic relation thereto, and a locking member being provided between said tubular member and said rod to lock said tubular member and rod in selected relative positions and to prevent relative axial movement therebetween.
